UNITED STATES PATENT OFFICE.

FREDERICK G. TREUBIG, OF NEW YORK, N. Y.

TOY.

Application filed March 27, 1923. Serial No. 628,038.

To all whom it may concern:

Be it known that I, FREDERICK G. TREUBIG, a citizen of the United States of America, and resident of New York city, in the 5 county of New York and State of New York, have invented certain new and useful Improvements in Toys, of which the following is a specification.

This invention relates to toys, and particularly to collapsible or foldable toy furniture.

An object of this invention is to produce a device having parts which may be adjusted to convert the toy into a bed or a sofa, self-contained means being provided for locking the parts together to hold them in their different positions of adjustment.

It is a further object of this invention to produce a toy of the character indicated 20 which can be constructed almost wholly by the stamping processes, and preferably of sheet metal with integral interlocking means to produce joints that are strong and durable, as well as efficient.

It is a further object of this invention to produce a toy of the character indicated, the parts of which can be collapsed or folded to occupy comparatively little space.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a perspective view of the device when adjusted to produce a bed;

Figure 2 illustrates a view in elevation showing the parts collapsed or folded;

Figure 3 illustrates a perspective view 45 when the parts are adjusted to produce a sofa;

Figure 4 illustrates a fragment of the device showing one end in a different position of adjustment; and

Figure 5 illustrates a sectional view of a joint between sections of the device.

In these drawings, 10 denotes one of the bottom sections and 11 the other bottom section when the device is adjusted to be used 55 as a bed, but one of the said sections constitutes the back and the other the seat when

the device is adjusted to produce a sofa. The parts, or plate-like members, 10 and 11 are interchangeable as to their being used as a seat or back when the sofa is formed, and 60 the said sections are hinged on a rib or wire 12 which forms what may be termed the frame of the structure it being shown that the said rib has a downwardly extending loop 13 at the end of the sections and that 65 the said rib terminates in an upwardly extending portion 14, which constitutes a pintle on which the end wings 15 and 16 are hinged. The parts are duplicated at each 70 end of the frame, and therefore, a description of the wings and their mounting at one end will suffice for an understanding of the invention by one skilled in the art.

Each section 10 and 11 has ears 17 projecting from its ends, and the said ears are 75 preferably bent downwardly slightly to form hook-like extensions that enter slots 18 that are formed in the wings with which they engage.

The wings 15 and 16 are formed to the 80 general contour of the ends of benches with projections such as 19 at their outer corners that extend downwardly to form the legs or feet by which the device is supported.

Each wing has a recess 20 at its inner edge 85 which aligns with an ear of one of the sections 10 or 11 when the parts are folded, so that these recesses form clearances for the reception of the ears in order to permit the wings to fold closely against the sections 90 10 and 11 when the device is not in use. The relations of parts just described are shown in Fig. 2 of the drawing.

Any suitable means may be provided for 95 preventing the wings from being displaced from the pintles or ends of the frame, and usually, the upsetting of the ends of the frame or pintles will suffice as a sufficient means for preventing their disengagement.

The purpose of having the looped portions 13 is to increase the length of the pintle to provide for a separation of the bearings for the wings, and they also form abutments to limit the degree of oscillation 100 of the sections.

I claim:

1. In a toy, a frame comprising a rib and angularly disposed pintles, plate-like members each having an edge oscillatably mounted on the rib, pairs of wing members at the 110 ends of the plate-like members, each wing member of a pair having its edge oscillat-

ably mounted on one of the pintles, and means for effecting an interlocking engagement between each plate-like member and one of the wings at each end.

- 5 2. In a toy, a frame comprising a rib having downwardly extending loops and upwardly extending terminals constituting pintles, sections oscillatably mounted on the

rib, wings oscillatably mounted on the said pintles, ears projecting from the ends of the sections having interlocking engagement with the wings, the said wings having recesses to form clearances for the ears when the parts are in folded positions.

FREDERICK G. TREUBIG.
